DRIVEN CONCRETE PILE.

Specification of Letters Patent.

Patented Apr. 11, 1916.

1,178,531.

Application filed November 2, 1914. Serial No. 869,788.

To all whom it may concern:

Be it known that I, KIRBY DONALD MACLEAN, a citizen of the United States, residing in the city and county of San Francisco and State of California, have invented new and useful Improvements in Driven Concrete Piles, of which the following is a specification.

This invention relates to concrete pile construction and pertains especially to improvements in concrete socket piles of the character shown and described in my prior Patent #1,074,275, dated September 30, 1913. In this prior patent I have shown a concrete socket pile embodying a monolithic reinforced concrete body portion solid in cross section with its lower end having an internal elongated socket in which is fitted the upper end of a timber pile or extension, which 20 timber pile or extension by reason of its connection with the reinforce concrete body will be held in alinement with said body and the whole structure driven by power applied to the upper end of the pile as a 25 unit after the manner of driving ordinary piles by machinery now in use.

In practice it has been found that reinforced concrete piles when driven must in order to prevent shattering have their upper ends protected by some sort of a cushion block. After the pile has been driven it has then been customary to knock away the concrete at the upper end to expose the reinforcing rods by which the superstructure 35 may be bound to the pile.

One object of the present invention is to provide ways and means by which the pile when cast may be left with the ends of the reinforcing rods projecting the desired distance beyond the body of concrete and at the same time to allow the pile to be driven without interfering with the rods and without injury to the pile. It has also been found difficult heretofore to erect these concrete socket piles in deep water without having the wooden pile of excessive length, owing to the fact that the wood pile has got to be driven below the mud line. In some cases in deep water and comparatively shallow driving bottom it may be difficult to set the wooden pile properly below the mud line. Hence, one object of the present invention is to provide ways and means by which I can use any desired length of concrete pile

with just sufficient length of wooden pile 55 to provide the desired anchorage.

Another thing discovered in connection with the use of the concrete socket pile was the necessity of making a rigid bond or union between the concrete pile and the 60 wooden pile. This result is accomplished in the present invention and by the means hereinafter to be described.

The invention consists of the parts and the combination and construction of parts 65 as hereinafter more fully described and claimed, having reference to the accompanying drawings, in which—

Figures 1, 2 and 3 are vertical sections. Fig. 4 is an isometric projection of the cushion block. Fig. 5 is a perspective of the upper end of the pile. Fig. 6 is a sectional view of the assembled invention illustrating its use.

A represents a precast pile of reinforced 75 concrete molded in suitable forms prior to driving. It is fitted on the end with a socket 2 for superimposing upon a wooden pile 3. The concrete pile A and socket 2 are suitably reinforced by vertical corrugated bars 4 80 wrapped with wire 5. In practice the socket is usually wrapped on a 3 inch pitch and the shaft on a 6 inch pitch. By my method of driving, the longitudinal reinforcing bars 4 are allowed to project a foot or more 85 beyond the cast body of concrete. This is highly desirable so as to enable the formation of a flat upper end of the pile suitable for the receipt of the super-structure. In order to drive a pile with these projecting 90 ends I employ a cushion block 6 of wood, which is bored with longitudinal holes 6 corresponding to the projecting ends of the rods 4 with the flat end of the block adapted to rest on the flat upper end of the concrete 95 pile; and this block 6 is suitably reinforced by heavy iron bands 7.

In using concrete socket piles it is customary to use a wooden pile of a length that when driven its top will be a foot or two below the mud line. When working in shallow water and soft foundations one may use a wooden pile and drive it to within a short distance of the water line and then fit the concrete socket pile over it and drive the 100 two into position. Where working in deep water, or where the depth of the penetrable bottom is less than the depth of the water 105

thereby requiring a wooden section of less length than the depth of water, it has not been possible to follow the above method. Consequently in casting the concrete pile I have embedded into the head of the socket a suitable number of heavy pointed spikes 8 of suitable size and number that instead of driving the wooden pile first alone, it is suspended vertically from the driving machine in such position that the concrete section can be readily lowered over it, and by its weight forcing the spikes into the head of the wooden pile as shown in Fig. 1 sufficiently to suspend it from the socket pile when the two are lowered as a unit through the water and into the mud.

Before submerging the socket end of the concrete pile and at a point near where the bottom of the socket would come, a mortar 20 tight collar or gasket 9 of burlap or other suitable material is placed around the wooden pile so as to inclose an annular chamber 10 between the wooden pile and the inner walls of the socket, into which 25 suitable grout is filled through a small pipe 11 embedded at the shoulder of the socket. In operation the concrete section is suspended a few inches above its final seat thereby providing space for an excess of the 30 grout. This grout fills all the space 2' in the socket as shown more particularly in Fig. 2 not occupied by the wood; the pipe 11 then being capped. The socket pile with its wooden end 3 is dropped into place forcing the wooden pile into its final position 35 and thereby forcing under great pressure the extra grout into all the voids so as to effectually form the joint between the concrete and wood sections by providing the 40 greatest possible density of grout to give a maximum adhesion between the grout and the wood on the one hand, and the grout and the concrete on the other, thereby providing a rigid closure between the two parts 45 of the combination. The wooden cushion 5 is then slipped over the projecting ends of the longitudinal reinforcing rods 4 and also to rest on the concrete. The combined pile is then driven into place immediately.

50 The joint formed between the concrete pile and the wooden pile after setting has as much or more strength than any other section of the pile, as shown by various tests made.

55 Any type of super-structure can be used. Such pile is immune from decay, fire, or marine insect attack, since there is a solid con-

crete construction from a short distance below the mud line upward; the wooden pile being practically ever-lasting below mud. 60 By means of the wooden cushion 6 with the recesses 6 to receive the exposed ends of the reinforcing rods, the pile can be driven without shattering and without bending the reinforcing rods. This is quite an important 65 constructional feature.

Having thus described my invention, what I claim and desire to secure by Letters Patent is—

1. A reinforced concrete pile having a 70 socket in one end thereof to receive a wooden pile, a wooden pile of less diameter than said socket inserted therein, means for loosely suspending said wooden pile within the socket and out of contact with the concrete pile, a gasket around said wooden pile for closing the lower end of said socket, and means for filling the chamber around said wooden pile.

2. A reinforced concrete pile having a 80 socket in one end thereof to receive a wooden pile, a wooden pile of less diameter than said socket inserted therein, means for loosely suspending said wooden pile within the socket and out of contact with the concrete pile, a gasket around said wooden pile for closing the lower end of said socket, and means for filling the chamber around said wooden pile, said filling being compressed by forcing said wooden pile into final position with one end in contact with the head of said socket.

3. The process of forming a pile which consists in suspending a wooden pile within the socket of a suitably constructed concrete 95 pile and out of contact therewith to provide a space on all sides thereof, filling said space with grout, and then forcing said wooden pile into the socket to pack the grout.

4. The process of forming a pile which 100 consists in loosely suspending a wooden pile in the socket of a suitably constructed concrete pile in such manner as to provide a space above the head of the pile, filling said space with grout, and then forcing the 105 wooden pile into the socket to displace the grout from above the head thereof.

In testimony whereof I have hereunto set my hand in the presence of two subscribing witnesses.

KIRBY DONALD MacLEAN.
